REPEATER FOR WEFT REPLENISHING
LOOMSVictor H. Jennings, Worcester, Mass., assignor to
Crompton & Knowles Loom Works, Worcester,
Mass., a corporation of Massachusetts

Application January 29, 1944, Serial No. 520,263

20 Claims. (Cl. 139—232)

This invention relates to improvements in weft replenishing looms and it is the general object of the invention to provide improved mechanism by which a shuttle can be replenished by bobbins drawn from three stacks of a four-stack magazine.

In the weaving of certain fabrics using two types of weft, one of the wefts is consumed much more rapidly than the other and the shuttle weaving the first type requires replenishment much more rapidly than the other shuttle. An example of such fabrics are curtains which have a ground weave of fine weft and stripes of a coarse decorative weft. In my copending application Serial No. 490,155, filed June 9, 1943, I have shown a loom in which two stacks of the magazine may be used for the replenishment of one shuttle. That application sets forth a rocking lever which controls a stop having two positions and movable into and out of stopping position with respect to the stack selector to effect delivery of bobbins alternately from the two stacks for successive replenishments of the corresponding shuttle. It is an important object of my present invention to provide means by which the principles set forth in the aforesaid application can be extended to apply to three stacks of bobbins.

In the type of weft replenishing mechanism to which my invention more particularly applies there are employed vertically reciprocable bobbin releasers which have an up motion when transfer is initiated and then have a down motion when the magazine is set for completion of transfer. It is another object of my present invention to provide means by which the principles set forth in the aforesaid application can be extended to apply to three stacks of bobbins.

In the type of weft replenishing mechanism to which my invention more particularly applies there are employed vertically reciprocable bobbin releasers which have an up motion when transfer is initiated and then have a down motion when the magazine is set for completion of transfer. It is another object of my present invention to provide a lever which shall cooperate with three stack releasers and assume three different positions derived from the three releasers. A three-step stop is connected to the lever and moves under control of the lever so that its stops become successively operative to register the selector with the three releasers, one at a time, in a definite rotation which will effect uniform depletion of the bobbins of the three stacks.

It is another object of my present invention

to provide a selector stop controlling lever which shall be turned in one direction by two bobbin releasers when they operate and shall be turned in the opposite direction to return to normal starting position by a third releaser when the latter operates. In this way the last of a series of releasers can be made to return the stop control lever to starting position.

With these and other objects in view which will appear as the description proceeds, my invention resides in the combination and arrangement of parts hereinafter described and set forth.

In the accompanying drawings, wherein a convenient embodiment of my invention is set forth,

Fig. 1 is a side elevation of a multi-cell weft replenishing mechanism viewed from the center of the loom and having my invention applied thereto,

Fig. 2 is a vertical section on line 2—2 of Fig. 1, showing the parts in normal position,

Fig. 3 is a view similar to Fig. 1 but showing the lever in the position which it occupies for delivery of bobbins from the second stack,

Fig. 4 is a view similar to Fig. 3 but showing the lever in position corresponding to the delivery of bobbins from the third stack,

Fig. 5 is a perspective view of the three-step stop which controls the position of the selector,

Fig. 6 is a diagrammatic view of a loom of the type to which my invention can be applied,

Fig. 7 is a detail vertical section on line 7—7, Fig. 1, on an enlarged scale,

Fig. 8 is similar to a portion of Fig. 2 but indicating the operation of the lever actuating hooks.

Referring to Fig. 1, I have shown a loom frame 10 supporting a magazine M which in the present instance is of the multi-color type and is provided with four stacks of bobbins 11, 12, 13 and 14. The stacks of bobbins 11, 12 and 13 are all of the same general kind and preferably are of coarse or heavy weft, while the stack 14 is of fine weft such as may be used for the weaving of the ground of curtain fabrics. The stacks are associated with bobbin releasers 15, 16, 17 and 18, each of which cooperates with a bobbin cradle 19 at the lower end thereof. These releasers are normally down and the corresponding cradle empty, but when replenishment is indicated one of the releasers rises to rock its cradle in well-known manner to receive the bobbin from the associated stack, after which depression of the previously raised releaser rocks the

cradle in the opposite direction to discharge the bobbin therein and the bobbin drops to transfer position under the transerrer arm part of which is shown at 20. Each releaser is provided with a top lug 21 by means of which the releaser is raised and a bottom lug 22 by which the releaser is depressed.

The magazine is provided with a stack or releaser selector 25 including in its construction a casting 26 from which project laterally front and back fingers 27 and 28. A rod or shaft 29 carries the casting 26 and slides horizontally in front and back bearings 30 and 31 carried by an inside plate 32 of the magazine on which the releasers are mounted. The shaft 29 has secured at the rear end thereof a slotted collar 35 cooperating with the upper end of a positioning lever 36 pivoted at 37 to the magazine.

The weft detector D is mounted in front of the shuttle box B on the lay L and controls the position of a pin 40 which cooperates with a lever 41 floating on the upper end of a vertically reciprocating rod head or block 42. Lever 41 is connected by rod 43 to an arm 44 operatively associated with a fin 45 formed as part of the selector casting 26. When a shuttle is in box B and the lay moves to front center, the detector has a detecting operation and if sufficient weft is present in the shuttle, pin 40 moves forwardly or to the right as viewed in Fig. 1, out of the path of lever 41 as the latter is moved down by a descending movement of block 42 and rod 43 remains at rest. If, on the other hand, the detector indicates exhaustion of weft in the shuttle, pin 40 remains in the path of lever 41 and as the block 42 descends it causes the lever to lower rod 43 and thereby rock the selector in a counter-clockwise direction as viewed in Fig. 2 to raise the releaser registered with the selector. This angular movement of the selector occurs while the shuttle is at the magazine end of the loom.

After the shuttle has been picked to the opposite side of the loom and time has been allowed for shifting of shuttle boxes G at that end, see Fig. 6, block 42 rises and lifts lever 41, thereby causing the latter to raise rod 43 and rock the selector in a clockwise direction as viewed in Fig. 2 to lower the previously raised releaser. This rocking of the selector occurs every second pick of the loom shortly after the interval during which the shuttle boxes shift.

As shown in Fig. 6 a gang G of shuttle boxes at the left end of the loom includes upper and lower cells 50 and 51 which contain shuttles S' and S², respectively. By means of a box lifter rod 52 under control of pattern box shifting mechanism not shown the gang shifts so that the boxes 50 and 51 are alternately in active position and aligned with the race plate 53 of the lay L. In the present instance shuttle S' carries coarse weft to be employed as decorative stripes in a fabric having a fine ground woven by weft carried in shuttle S². The gang therefore is down when a coarse weft is being woven and up when the fine weft is being woven. The stripes of coarse weft are narrow, generally comprising only two or four picks so that shuttle box 51 becomes active at frequent intervals during the weaving operation.

Extending from the gang G is a connector 55 which leads from the drop box end to the magazine end of the loom and then extends upwardly to be connected to the arm 56 of the previously described lever 36. Lever 36 is so proportioned

that when box 50 is active spring 57 can move lever 36 to its extreme right hand position as viewed in Fig. 1 corresponding to the frontmost position of the selector 25, but when box 51 is active lever 36 moves to its rearmost position corresponding to registry of the selector 25 with the rear releaser 18.

The magazine has a second shaft 60 journaled in the upper part thereof and has fastened thereto a casting 61' provided with a shelf 61 for co-operation with dogs 62, one of which is pivoted on each of the releasers. Ordinarily these dogs are in the idle inactive position shown in Fig. 2 when the releaser is down. When a releaser is raised, however, its dog springs to the left as viewed in Fig. 2 to its operating position above shelf 61 and upon subsequent depression of the releaser the dog engages the shelf to turn shaft 60 in a clockwise direction as viewed in Fig. 2. The effect of this clockwise movement of shaft 60 is to lower a rod 63 connected to arm 63' on shaft 60 for the purpose of raising the transfer latch 64 into the path of a transfer bunter 65 on the lay and also raising rod 66 connected to arm 66' on shaft 60 to move a shuttle position detector or feeler 67 from its normal forward position to its rear position. This latter movement occurs while the lay is in the back part of its stroke and the lower part of the member 67, which customarily carries a thread cutter, is free to move rearwardly. As the lay moves forwardly it engages the shuttle detector 67 and rocks the same forwardly, thereby exerting a downward pull on rod 66 to effect a counter-clockwise movement of shaft 60, Fig. 2, and return the shaft and its shelf 61 to normal position.

Each of the dogs of the releasers 15, 16 and 17 has an upwardly extending hook 70 integral therewith, see Fig. 2. The head 71 of each of these hooks is normally spaced away from the plate 32, but when any of these three releasers rises the corresponding hook 70 moves toward the plate 32 simultaneous with movement of the dog 62 to operating position over shelf 61. Upon subsequent descent of the releaser its head 71 moves down along a path adjacent to the plate 32 until the releaser nears the bottom of its movement, whereupon the dog 62 and hook 70 are rocked back to their normal position against the action of spring 72 by the engagement of a lug 73 on dog 62 and a part of plate 32.

The matter thus far described, except for hook 70 and the leverage of lever 36, are of common construction and operate in the usual manner. The hooks 70 are somewhat similar to hooks shown in my aforesaid co-pending application and perform the same general function as set forth in that application. When the selector rocks in a counter-clockwise direction as viewed in Fig. 2, one or the other of its fingers 27 or 28 will engage the top lug 21 of the releaser registered therewith to effect upward movement of the releaser, and subsequent rocking of the selector in a clockwise direction as viewed in Fig. 2 will cause the finger to engage the lower lug 22 for the purpose of returning the raised releaser to its normal down position. The selector can shift laterally so that it registers with each of the four releasers, one at a time.

In carrying my present invention into effect I secure a plate 75 to the magazine frame 32 and provide it with a stud 76 on which is pivoted a lever 77. The pivot 76 is preferably located between the second and third releasers 16 and 17, respectively, and has a relatively long front

arm 78 having two operating surfaces 79 and 80 at different levels, the latter surface being higher than the former. Extending rearwardly of the pivot 76 is a relatively short arm 81 having a working surface 82. The surfaces 79, 80 and 82 are adapted for cooperation with the hook heads 71 of the releasers 15, 16 and 17, respectively.

In order that lever 77 may be held in any angular position to which it may be moved, I provide the friction device shown in Fig. 7. Between lever 77 and nut 90 on the stud 76 I place a compression spring 89 to create frictional force between the plate 75 and lever 77 to hold the latter stationary in any position it may assume.

A rod 95 is formed with a slot 96 in its upper end to receive a stud 97 on the right end of lever 77, Fig. 3 and extends downwardly for attachment to a stop 98 which, as shown in Fig. 5, is of inverted U-shape and has arms 99 which straddle the shaft 29 to be guided by the latter as the stop rises and falls. The stop has a right edge 100 adapted for engagement with bearing 30 which limits movement of the stop to the right as viewed in Fig. 1.

The stop is provided with three vertical stop surfaces 101, 102 and 103 which correspond, respectively, to releasers 15, 16 and 17. The stop is capable of three vertical positions as will be described and as it descends, the surfaces 101, 102 and 103 move successively to stopping position between bearing 30 and the casting 26 to limit movement of the selector to the right, Fig. 1, under action of spring 57.

In operation it may be assumed that arm 78 is in its highest position and that stop 98 is up, so that stop surface 101 cooperates with spring 57 to register the selector 25 with front releaser 15 which is in down position, see Fig. 1. These conditions can exist when gang G is down and shuttle S' and shuttle box 50 are active. If upon arrival at the magazine end of the loom shuttle S' gives indication of weft exhaustion the selector will be rocked as already described and finger 27 will engage lug 21 of releaser 15, raising the latter so that its hook 70 will move from the full line to the dotted line position, see Fig. 8, to place head 71 over surface 79 on arm 78. As releaser 15 descends upon subsequent arrival of shuttle S' in box B, the hook head 71 will give the lever 77, a partial rotation in a clockwise direction as viewed in Fig. 1, thereby lowering stud 97 and permitting the rod 95 and stop 98 to fall until it rests on the casting 26. The replenished shuttle S' is then picked to the opposite side of the loom and because of the characteristic of the fabric being woven there will be a shift of the gang G upwardly to place box 51 and shuttle S² in action. This shift of the gang G creates a pull in the connector 55 and arm 36 moves to its rearmost position with finger 28 in register with releaser 18. During this rearward movement of the selector 25 the stop 98 will complete its falling movement and place surface 102 in the path of casting 26.

When shuttle S' next returns to action there will be a slackening of the tension in connector 55 and spring 57 will try to move the selector back to its front position, but the stop surface 102, now being in stopping position, will arrest forward movement of the selector and register finger 27 with releaser 16, see Fig. 3. These conditions will continue until shuttle S' requires another replenishment, whereupon slide 16 will

be raised and in its descent the hook 70 thereof will engage surface 80 of arm 78 and give lever 77 another partial right hand rotation resulting in a further downward movement of stud 97. Rod 95 and stop 98 therefore fall and upon movement of the selector to its rearmost position the stop 98 will complete its downward motion to place stop surface 103 in the path of casting 26. Upon subsequent return to action of the shuttle S' the selector will be stopped by surface 103 with its finger 28 in register with releaser 17, see Fig. 4.

The third replenishment of shuttle S' will result in a reciprocation of releaser 17, and as the latter descends its hook 70 will engage surface 82 of the arm 81 and rock lever 77 in a counter-clockwise direction around its pivot as viewed in Fig. 4. The pivot 76 and the lengths of the arms 78 and 81 are so related that down motion of the hook on releaser 17 will rock lever 77 back to its starting position with arm 78 all the way up. The parts are now set to repeat the operations already described and as successive replenishments occur bobbins are drawn from the stacks in the order 11, 12, 13—11, 12 and 13, etc. The bobbins are therefore drawn from these three stacks at a uniform rate and their full capacity can be utilized for replenishment of shuttle S'.

It will be understood that if shuttle S² gives indication of exhaustion it will be replenished from the rear stack 14 in the usual manner at any time when shuttle S² is in box B regardless of the position of lever 77.

I have chosen to describe my invention in connection with a loom weaving a fabric having two types of weft, the weft in shuttle S' and stacks 11, 12 and 13 being relatively large, while the weft in shuttle S² and stack 14 is relatively fine or small. One bobbin drawn from stack 14 will ordinarily last as long as two or more bobbins, drawn from stacks 11, 12 and 13. I do not wish, however, to be limited to this type of fabric in the practice of my invention, inasmuch as it is sufficient if the selector 25 moves rearwardly in time to allow the stop 98 to move to its proper stopping position subsequent to one replenishment of shuttle S', and before the next replenishment of that shuttle.

From the foregoing it will be seen that I have provided simple means for replenishing one shuttle from three stacks of a magazine by the use of a lever and multi-step stop operated by the releasers 11, 12 and 13. It will further be seen that replenishment involving a bobbin drawn from stack 13 restores lever 77 to a position where a second sequence of bobbin releasers can start with stack 11. It will further be seen that a single lever adapted for rocking in opposite directions by the bobbin releasers is utilized to give the stop 98 its several positions and also insure the starting of another sequence of releasers upon completion of the preceding sequence.

Having thus described my invention it will be seen that changes and modifications may be made therein by those skilled in the art without departing from the spirit and scope of the invention and I do not wish to be limited to the details herein disclosed, but what I claim is:

1. In a weft replenishing loom having three stacks of bobbins each provided with a bobbin releaser operated by a selector movable to register with the releasers, one at a time, the loom having actuating means to move the selector away from registry with any releaser and subsequently return said selector to registry with one or another of the releasers, a stepped stop capable

of assuming three positions in each of which said stop registers the selector with a different releaser, and a controller for said stop moved to three different positions by said releasers operating one at a time and when in each position thereof of cooperating with said actuating means to effect movement of the stop to a different one of the three positions thereof.

2. In a weft replenishing loom having three stacks of bobbins each provided with a bobbin releaser operated by a selector movable to register with the releasers, one at a time, the loom having actuating means to move the selector away from registry with any releaser and subsequently return said selector to registry with one or another of the releasers, a stepped stop capable of assuming three positions in each of which said stop registers the selector with a different releaser, and a controller for said stop movable to three different positions and cooperating with said actuating means to move the stop to the three positions thereof, one position of the stop for each position of the controller, each releaser upon operation thereof by said selector changing the position of the controller and causing the latter in cooperation with said actuating means to cause the stop to register the selector with the next releaser to be operated thereby.

3. In a weft replenishing loom having three bobbin releasers operated by a selector registerable with the releasers one at a time, the loom having actuating means to move the selector away from registry with any releaser and subsequently return the selector to registry with one or another of said releasers, a selector stop capable of occupying three different positions, one position for each releaser, and when in any position cooperating with the actuating means to register the selector with the corresponding releaser, and a controller for said stop moved by said releasers to three different positions, one position for each releaser, depending upon which releaser moves the controller, said controller when in a position corresponding to any given releaser cooperating with the actuating means to effect movement of the stop to the position thereof corresponding to the given releaser.

4. In a weft replenishing loom having three bobbin releasers operated by a selector registerable with the releasers one at a time, the loom having actuating means to move the selector away from registry with any releaser and subsequently return the selector to registry with one or another of said releasers, a selector stop capable of occupying three different positions, one position for each releaser, and when in any position cooperating with the actuating means to register the selector with the corresponding releaser, and a controller for the stop operated by the releasers, one at a time, and cooperating with the actuating means to effect movement of the stop to the three positions thereof.

5. In a weft replenishing loom having three bobbin releasers operated by a selector registerable with the releasers one at a time, the loom having actuating means to move the selector away from registry with any releaser and subsequently return the selector to registry with one or another of said releasers, a selector stop capable of occupying three different positions, one position for each releaser, and when in any position cooperating with the actuating means to register the selector with the corresponding releaser, and a lever connected to said stop and receiving two separate movements to two differ-

ent positions from two of the releasers, one releaser for each position, and receiving a third movement to a third position by the third releaser, each of the three positions of the lever corresponding to a different position of the stop, and the actuating means cooperating with the lever when the latter is in any of the positions thereof to effect movement of the stop to the position thereof corresponding to the position of the lever.

6. In a weft replenishing loom having three bobbin releasers operated by a selector registerable with the releasers one at a time, the loom having actuating means to move the selector away from registry with any releaser and subsequently return the selector to registry with one or another of said releasers, a selector stop capable of occupying three different positions, one position for each releaser, and when in any position cooperating with the actuating means to register the selector with the corresponding releaser, a lever pivoted intermediate the ends thereof and having one end operated by two of said releasers, one at a time, to move said lever to two positions, one position for each of said two releasers, and the lever having the other end thereof operated by the third releaser to move the lever to a third position, the releasers when operated in rotation moving the lever successively to three different positions, and the actuating means cooperating with the lever when the latter has said successive movements to effect successive movements of the stop to the three positions thereof to effect registry of the selector progressively with the releasers.

7. In a weft replenishing loom having three bobbin releasers operated by a selector registerable with the releasers one at a time, the loom having actuating means to move the selector away from registry with any releaser and subsequently return the selector to registry with one or another of said releasers, a selector stop capable of occupying three different positions, one position for each releaser, and when in any position cooperating with the actuating means to register the selector with the corresponding releaser, a lever moved in one direction to two different positions by two of said releasers acting one at a time and moved in the opposite direction to a third position by the third releaser, each position of the lever corresponding to a different one of said three positions of said stop, said lever when moving to the positions thereof cooperating with said actuating means to effect movement of the stop to the three positions thereof.

8. In a weft replenishing loom having three bobbin releasers operated by a selector registerable with the releasers one at a time, the loom having actuating means to move the selector away from registry with any releaser and subsequently return the selector to registry with one or another of said releasers, a selector stop capable of occupying three different positions, one position for each releaser, and when in any position cooperating with the actuating means to register the selector with the corresponding releaser, an operating hook on each releaser, a lever pivoted intermediate the ends thereof and having one arm for operation by the hooks of two of said releasers when the latter operates one at a time to move the lever to two different positions and having another arm for operation by the hook of the third releaser when the latter operates to move the lever to a third posi-

tion, said two releasers when operated in order by the selector, one at a time, causing the hooks thereof to move the lever successively in one direction to two different positions thereof and the third releaser when operated by said selector subsequent to operation of said two releasers causing the hook thereof to move the lever in the opposite direction to the third position thereof, said actuating means cooperating with said lever when the latter moves progressively to the three positions thereof to move said stop progressively to the three positions thereof.

9. In a weft replenishing loom having three stacks of reserve bobbins each provided with a bobbin releaser operable by a selector, movable into register with the releasers, one at a time, provision being made to move the selector away from registry with any releaser after operation of any releaser by the selector and subsequently return the selector for registry with one or another of said releasers, a controller moved in one direction to two different positions by operation of two of said releasers, one at a time, by said selector and moved in another direction to a third position by operation of the third releaser by said selector, and stop means connected to said controller and moving to three different positions with respect to the selector, one position of said stop for each position of said controller, to stop said selector in register with each of said releasers, one at a time.

10. In a weft replenishing loom having three stacks of reserve weft and wherein each stack has a bobbin releaser operated by a selector common to the releasers and movable along a given path to register with the releasers, one at a time, actuating means to move said selector along said path away from registry with any releaser and thereafter return the selector along said path to registry with one or another of said releasers, a multi-step stop capable of moving progressively to three different positions relatively to said path to register said selector in rotation with the releasers, and mechanism operated by the releasers in rotation and cooperating with said actuating means to effect progressive movement of said stop to said three positions thereof.

11. In a weft replenishing loom having three stacks of similar reserve bobbins and having a fourth stack of different bobbins, the loom operating with a bobbin releaser for each stack operable by a selector movable along a given path to register with all of said releasers, one at a time, and the loom having actuating means to move the selector into registry with the releaser of the fourth stack and then return the selector to registry with one or another of the releasers of said three stacks, a stop having steps movable into and out of said path and assuming three positions relatively to said path, one position for each of said three stacks, a controller operatively connected to said stop and moved in one direction by one releaser to one position to move the stop away from said path to one of the positions thereof and said controller moved in the opposite direction by the other two releasers, one at a time, to two other different positions and cooperating with said actuating means to effect movement of the stop to two different positions in said path.

12. In a weft replenishing loom having three stacks of similar reserve weft each having a releaser and having a fourth stack of different weft, the loom having a selector to register with

and operate each releaser, one at a time, the loom having actuating means to move the selector into registry with the fourth stack subsequent to an operation of any of said releasers by said selector and thereafter return the selector to registry with one or another of said releasers, a controller moved in one direction to two different positions by two of said releasers when the latter are operated by said selector, and a multi-step stop connected to said controller and the latter cooperating with said actuating means to effect movement of said stop relatively to the selector to three different positions, one position of said stop for each of the three positions of the controller, said stop when in each position thereof cooperating with said actuating means to register the selector with a different one of said three releasers.

13. In control mechanism for a weft replenishing loom bobbin stack selector registerable with three bobbin releasers, one at a time, for operation thereof, a lever having an arm provided with two operating areas at different levels which cooperate with two of said releasers, one releaser for each of said areas, the other arm having an area for cooperation with the third releaser, a positioning member for said selector operatively connected to the lever and having steps movable toward and away from operative relation with respect to the selector, engagement of said two releasers in order with their respective areas effecting movement of the lever in one direction to effect movement of said positioning member toward operating position with respect to the selector, and movement of the lever by engagement of the third releaser with the area corresponding thereto causing movement of the lever in the opposite direction to effect movement of said positioning member away from operating position with respect to the selector.

14. In control mechanism for the selector of a weft replenishing loom operating with three bobbin releasers, said mechanism comprising a lever, a pivotal support for the lever intermediate the ends thereof, an arm on one side of said pivotal support for cooperation with one of said releasers, a second arm on the other side of said pivotal support for cooperation with the other two releasers, one at a time, at points differently spaced from said pivotal support, one point for each of said two releasers, and a multi-step stop for the selector connected to said lever.

15. In control mechanism for a weft replenishing loom bobbin stack selector registerable with three bobbin releasers, one at a time, for operation thereof, positioning means for the selector movable to three different positions to determine with which releaser said selector shall register, and a controller for the positioning means movable to three different positions, each position of said controller corresponding to a different one of said three positions of the positioning means, two of said releasers when operated in sequence by said selector shifting the controller from a starting position corresponding to one of the three positions thereof in sequence to two other positions, and the third releaser when operated thereafter by said selector shifting the controller back to said starting position.

16. In control mechanism to cause a weft replenishing loom bobbin stack selected to register with each of three bobbin releasers in repeated sequences in each of which the selector regis-

ters with said releasers one after the other, a positioning member movable to three different positions relatively to said selector, each of said three positions of said member corresponding to registry of the selector with a different releaser, and control means for said positioning member by two of said releasers one after the other to move the member from a starting position corresponding to one of said three positions thereof to the other two of said three positions, one after the other, each of said two positions corresponding to a different position of said member relatively to said selector, and said control means operated thereafter by the third releaser to return the positioning member to said starting position.

17. In control mechanism for a weft replenishing loom bobbin stack selector, registerable with a plurality of bobbin releasers, one at a time, for operation thereof, positioning means for the selector movable to a number of different positions equal to the number of releasers, each position of said means corresponding to registry of said selector with a different releaser, and control means for the positioning means movable to a number of positions equal to said number and connected to said positioning means and each position of said control means corresponding to a different position of said positioning means, a group of said releasers when operated in sequence by said selector acting one by one to shift the control means from a starting position to a number of different positions equal to the number of releasers in said group, and one of said releasers other than those in said group acting when operated by said selector to move said control means back to said starting position.

18. In control mechanism for a multi-stack weft replenishing mechanism stack selector, a group of bobbin releasers with which the selector registers, one at a time, for operation there-

of, another releaser with which the selector registers for operation thereof when said selector is out of register with the releasers of said group, and positioning mechanism for said selector movable to as many different positions as there are total releasers, each position of the positioning mechanism corresponding to registry of the selector with a different releaser, the releasers of the group when operated in sequence by the selector moving the positioning mechanism from a starting position corresponding to one of said positions of said positioning mechanism to as many different positions as there are releasers in said group, and said other releaser when operated by the selector moving said positioning mechanism back to said starting position.

19. A control lever for the bobbin releaser selector of a weft replenishing mechanism operating with three bobbin releasers, said lever comprising two oppositely extending arms and a bearing between said arms, one of said arms having two different operating surfaces each for cooperation with a different one of two of said releasers and the other arm having an operating surface for cooperation with the third releaser.

20. A control lever for the bobbin releaser selector of a weft replenishing mechanism operating with three bobbin releasers, said lever comprising two arms extending in opposite directions from a bearing, one of said arms having a working surface at a given distance from said bearing for cooperation with one of said releasers and having a second working surface at a greater distance from said bearing and angularly displaced relatively to said bearing with respect to the first working surface for cooperation with another releaser, and the other arm having a third working surface for cooperation with the third releaser.
